CLAIM

The ornamental design for a pump, as shown and described.

DESCRIPTION

FIG. 1 is a top, front perspective view of a pump, showing our new design;

FIG. 2 is a bottom, rear perspective view of the pump of FIG. 1;

FIG. 3 is a top plan view of the pump of FIG. 1;

FIG. 4 is a front elevational view of the pump of FIG. 1;

FIG. 5 is a left end elevational view of the pump of FIG. 1;

FIG. 6 is a rear elevational view of the pump of FIG. 1;

FIG. 7 is a right end elevational view of the pump of FIG. 1;

FIG. 8 is a bottom plan view of the pump of FIG. 1;

FIG. 9 is a top back perspective view of the pump of FIG. 1; and,

FIG. 10 is a bottom front perspective view of the pump of FIG. 1.

The broken line showing is for illustrative purposes only and forms no part of the claimed design.
